E. J. W. DE FOREEST.
IDENTIFICATION TAG.
APPLICATION FILED JAN. 18, 1917.

1,260,156.

Patented Mar. 19, 1918.

UNITED STATES PATENT OFFICE.

EARL J. W. DE FOREEST, OF TULSA, OKLAHOMA.

IDENTIFICATION-TAG.

1,260,156.

Specification of Letters Patent. Patented Mar. 19, 1918.

Application filed January 18, 1917. Serial No. 143,125.

To all whom it may concern:

Be it known that I, EARL J. W. DE FOREEST, a citizen of the United States, residing at Tulsa, in the county of Tulsa and 5 State of Oklahoma, have invented certain new and useful Improvements in Identification-Tags, of which the following is a specification.

This invention relates to devices whereby 10 identification or name tags may be supported upon a structure and rendered inaccessible except by destroying a part of the supporting means.

The improved device may be applied to 15 various structures, but is more particularly applicable to automobiles, but it is not desired to limit the use of the device in any particular.

By employing the improved device the 20 automobile or other apparatus or structure is thus protected and its identification assured in event of its being stolen.

In the drawings illustrative of the preferred embodiment of the invention—

25 Figure 1 is a perspective view of the improved device.

Fig. 2 is a detached perspective view of the tag locking member.

Fig. 3 is a detached perspective view of 30 the base or support for the tag and the locking member.

Fig. 4 is an enlarged vertical section on the line 4—4 of Fig. 1.

Fig. 5 is a longitudinal section on the 35 line 5—5 of Fig. 1.

Corresponding and like parts are referred to in the following description and indicated in all the views of the drawings by the same reference characters.

40 The improved device comprises a base or holding portion including a rear plate 10 adapted to be attached to the structure which is to be protected, for instance some portion of a body of an automobile. The

45 member 10 will preferably be provided with a plurality of apertures 11 to receive holding screws when the device is applied to a wood or like structure, and likewise provided with slots 12 spaced apart to receive

50 holding clips 13 bent intermediate their ends, as shown in Fig. 5 and adapted to be passed through corresponding slots in the structure to which the device is to be attached, as for instance a plate or sheet metal

55 part of the automobile, a portion of which is indicated at 14. When secured by the

clips 13 one portion of the clip will be disposed within the member 14 while the other portion of the clip is disposed against the inner face of the member 10, as shown in 60 Fig. 5. The portion of the clip which engages the member 10 lies flatly against the same. The member 10 is likewise provided with resilient tongues 15 projecting inwardly therefrom near the lower edge, as 65 shown in Fig. 3.

The member 10 is provided at its ends with guard devices 16 and with a similar guard device 17 at the lower edge. The 70 terminal guard devices 16 are formed with inwardly directed flanges 18, while the bottom guard member 17 is provided with a similar stop shoulder 19, portions of the member 16—17 overhanging the stop shoulders, as shown at 20, while portions of the 75 guard member 17 overhang the stop shoulder 19, as shown at 21. The overhanging portions of the member 16—17 and the stop shoulders 18—19 form seats to receive a locking plate represented as a whole at 22, 80 a card 23 to receive a name or other identifying matter, and a transparent member of glass or the like and represented at 24. The member 22 is provided with a lateral rib 25 at its lower edge and a guard member 26 85 at the upper edge and with a lateral stop shoulder 27, a portion of the guard member overhanging the shoulder, as shown at 28.

The guard devices 16—17 together with 90 their overhanging portions 20 and stop shoulders 18—19 are substantially alike transversely, while the guard portion 26 with its overhanging portion 28 and stop shoulder 27 correspond transversely with the 95 other guard members. At their upper ends the guards 16—20 are beveled, while the terminals of the guard 26 are correspondingly beveled, so that when the member 22 is disposed within the seats of the members 100 16—17 the confronting ends of the guard members will be closely united, so that the several guard members present the appearance of a frame which completely surrounds the glass member and the identification card, 105 as shown in Fig. 1. When the member 22 is inserted within the seats of the guard members 16 and moved downwardly the rib 25 will engage the yieldable tongues 15 and effectually prevent the withdrawal of the 110 member 22. The member 22 is provided with apertures 29 which are so located that

the tongues 15 are accessible through the apertures when the member 22 is inserted, so that the tongues 15 may be detached from the rib 25 to release the member 25 by a 5 suitable implement inserted through the apertures 29.

At its upper edge the locking member 22 is provided with a rib 30 which overhangs the upper edge of the member 10.

- 10 The base member 10 having been applied to the supporting structure either by screws or bolts inserted through the apertures 11, or by means of the clips 13, the member 22 having the identification card 23 and the
- 15 glass member 24 disposed with their upper edges in the seat formed by the stop shoulder 27 and the overhanging portion 28 of the guard 26, is inserted in the seats formed by the overhanging portions 20 and the stop shoul-
- 20 ders 18 and moved downwardly until the rib 25 is engaged by the tongues 15. This movement will dispose the members 23-24 with their outer edges rearwardly of the overhanging portions 20-21 and 28. The parts
- 25 are thus locked together and cannot be separated except by breaking the glass member 24 and tearing the identification card loose to expose the apertures 11, which will enable the tongues 15 to be detached from the rib
- 30 25 and release the member 22, as before described.

The name of the owner of the automobile or other structure, or other identifying matter will thus be protected and rendered in- 35 accessible except by destroying the protecting glass member.

The improved device is constructed wholly of sheet or plate metal, preferably steel, and may be plated or otherwise ornamented, or 40 protected.

Having thus described the invention, what is claimed as new is—

1. A device of the class described, comprising a base having overhanging frame mem- 45 bers at three sides, means for attaching the base to a supporting structure, yieldable tongues carried by the base and extending into the space within the frame members, a locking member engaging the overhanging
- 50 portions of said frame members and having an inwardly directed rib engageable with the tongues, said locking member covering said

base holding means and rendering the same inaccessible and having a frame member corresponding to and coacting with the frame 55 members of the base, and a member engaging the overhanging frame members and preventing access to the tongues.

2. The combination with a support having slots therethrough, a base having slots 60 registering with the slots of the support, holding clips engaging intermediate their ends through said slots with the remaining portions directed laterally of the intermediate portion and bearing respectively 65 against the outer face of the base and the inner face of the support, overhanging frame members carried by the base at three edges thereof, yieldable tongues carried by the base and extending into the space within the frame members, a locking member engaging 70 the overhanging portions of said frame members and having an inwardly directed rib engageable with the tongues, said locking member covering the base engaging 75 portions of said clips and maintaining them in locked position and rendering the same inaccessible, a frame member carried by the locking member and corresponding to and coacting with the frame members of the 80 base, and a member engaging the overhanging frame members and preventing access to the tongues.

3. A device of the class described, comprising a base having overhanging frame 85 members at three sides, means for attaching the base to a supporting structure, yieldable tongues carried by the base and extending into the space within the frame members, a locking member engaging the overhanging 90 portions of said frame members and having apertures through which the tongues are accessible and provided with an inwardly directed rib engageable with the tongues, said locking member covering said base holding 95 means and rendering the same inaccessible and having a frame member corresponding to and coacting with the frame members of the base, and a member engaging the overhanging frame members and covering the 100 apertures of the locking member and preventing access to the tongues.

In testimony whereof I affix my signature.

EARL J. W. DE FOREEST. [L. S.]
